UNITED STATES PATENT OFFICE.

JESSE A. BOWLES, OF SPOKANE, WASHINGTON, ASSIGNEE OF ONE-HALF TO CHARLES H. HINKE, OF SPOKANE, WASHINGTON.

ELECTRICAL SNOW-MELTING HEATER.

1,203,179.

Specification of Letters Patent Patented Oct. 31, 1916.

Application filed April 1, 1915. Serial No. 18,593.

To all whom it may concern:

Be it known that I, Jesse A. Bowles, a citizen of the United States, residing at Spokane, in the county of Spokane and State of Washington, have invented certain new and useful improvements in Electrical Snow-Melting Heaters, of which the following is a specification.

This invention relates to improvements in electrical snow melting mechanism and has to do with that class of mechanism of this character which is incorporated in the structure of the street pavement or road way, in contradistinction to that class of snow melters which are mounted upon wheels to be advanced along the street or roadway.

The preferred mechanism constituting my invention is partly embedded in the pavement or roadway so as to be flush with the surface thereof and is disposed adjacent to the gutter toward which the street or roadway slopes but on that side of the gutter nearer the center of the street rather than on the sidewalk side and in such a manner that the water will run over the device of my invention into the gutter. In other words, the device of my invention is disposed in a manner to melt the snow and deliver the water to the gutter.

My invention also comprises a mechanism of this character composed of a series of containers or boxes which are disposed in spaced relation with respect to each other and along and adjacent the gutter of a roadway, the boxes or receptacles containing heat producing means which will heat the boxes to a sufficient temperature to melt the snow and cause the water to run into the gutters.

It is one of the special objects of my invention to provide an electrically operated snow melting mechanism, the boxes or receptacles, being provided with heating coils and electrical conductors connecting the several spaced receptacles with a source of current.

Other features and objects of the invention will be more fully described in connection with the accompanying drawings and will be more particularly pointed out in and by the appended claim.

In the drawings:—Figure 1 is a plan view of a street or road way equipped with the device of my invention. Fig. 2 is a sectional view on line 2—2 of Fig. 1. Fig. 3 is an elevation of one of the boxes or receptacles showing the same on an enlarged scale. Fig. 4 is a sectional view on line 4—4 of Fig. 3.

Like characters of reference designate similar parts throughout the different figures of the drawings.

As illustrated, 1 designates an arched street structure or pavement which slopes laterally toward gutters 2, the sidewalk being indicated at 3. The street car tracks are indicated at 4, and are disposed centrally with respect to the pavement or street structure. Manholes are indicated at 5, and sewer connections 6 lead downwardly to the sewer, the latter not being shown.

The mechanism of my invention is indicated generally at 7 and is disposed along the street structure adjacent to the gutters 2 but inside the latter with respect to the sidewalks 3.

By reference to Fig. 2, it will be noted that the mechanism of my invention is partly embedded in the structure so that the upper surface of such mechanism will be flush with the street surface. It is usual to clear a street or roadway from the center by throwing the snow laterally toward the gutter.

It is one of the objects of my invention to apply heat to the snow so that the water will pass over the mechanism of my invention and be delivered to the gutter.

As illustrated, my invention includes a series of receptacles or boxes 8 which are shown more particularly in Figs. 3 and 4. The boxes are shown disposed in rows adjacent the gutters and in such close relation that a practically continuous heated strip will be presented to the snow disposed adjacent to the gutters.

Referring to Figs. 3 and 4, 9 designates the bottom of the box and 10 designates the longer side walls. The end walls are designated at 11 and a removable lid or cover 12 is secured by means of screws 13. Suitable packing or gaskets 14 may be interposed between the cover 12 and that portion of the structure 10 to which the cover is applied. The upright side and end walls 10 and 11 are provided with a supporting flange 15 on which a tray formed of insulating material, is disposed, the tray being indicated at 16. In order to support the cover 12, between the upright walls of the box or receptacle, a supporting post 17 is formed on the bottom 9 and extends upwardly into supporting relation with the central portion of the cover 12. A lining is provided for the bottom portion of the box and is indicated at 18 and this lining

- may be of insulating material of any desired character. Heating coils 19 are disposed in the tray 16 and are electrically connected in series by conductors 20 and 21.
- 5 Each endmost coil 19 is connected by conductors 22 and 23, extending through a conduit 24, to the coils of the next adjacent box. A coupling 25, threaded into the side wall 10, forms a mechanical connection between adjacent receptacles. The conduit 24 extends through the coupling 25 into the next adjacent receptacle. Each receptacle is provided on each side with a coupling, such as 25, and the opposite end coil is connected by conductors 25' and 26 passing through a conduit 27 which extends through coupling 25.
- 10 The boxes, with their heating coils, will be connected in series and terminal conductors 22 and 23 will lead to a switch box 29. A source of current 30 diagrammatically indicated in Fig. 2, will be connected with each switch box to supply current for heating coils 19 of the several heating units. The switch boxes may be disposed at the end of 25 each group of heating units it being understood that in practice the units are connected for limited lengths of road way so that in case of repairs, only a short section will be temporarily thrown out of operation.
- 15 By reason of the fact that the boxes are relatively small, and because they are embedded in the roadway or pavement so that their tops will be flush with the latter, no great strain will be at any time imposed on 30 any one box and yet I am able to get a practically continuous heated strip or a sufficiently continuous heated strip so as to efficiently melt all of the snow just along the gutter. It will thus be seen that by disposing 35 the units in linear groups along a street, the utmost economy can be effected by reason of the fact that any one group can be

cut off when the snow is completely melted and the groups may be operated in accordance with the progress made and in accordance with the quantity of snow dumped or disposed adjacent the gutter.

45 While I have herein shown and described one specific form of my invention I do not wish to be limited thereto except for such 50 limitations as the claim may import.

I claim:

55 In an electric snow melting mechanism, snow melting means comprising a plurality of heating units in linear spaced relation along a roadway and each unit consisting of a metal box having a base and upright walls and provided with an upright lid supporting post and a supporting flange formed on 60 said walls and extending about the interior of said box, a lining of insulating material extending along and over said bottom and upwardly along the interior of said walls, a tray of insulating material disposed on said flange and being substantially co-extensive 65 in area with respect to the horizontal cross section of said box, electrical heating coils disposed in said tray, electrical conductors connecting said coils in series, electrical supply conductors leading through said walls to 70 and from end-most coils and extending through said bottom lining and through said tray, and a snow melting lid of metal mounted on said walls and post and closing said box and being in such close proximity to 75 said coils as to be heated thereby, substantially as described.

In testimony whereof I affix my signature in presence of two witnesses.

JESSE A. BOWLES.
